UNITED STATES PATENT OFFICE.

EMIL KARL AUGUST MEUMANN AND MAX JOSEPH HIRSCH, OF SCHÖNAU,
NEAR CHEMNITZ, GERMANY.

SEWING-MACHINE FOR MANUFACTURING SMOCKED PLAITS.

No. 838,348.

Specification of Letters Patent.

Patented Dec. 11, 1908.

Application filed September 22, 1905. Serial No. 279,668.

To all whom it may concern:

Be it known that we, EMIL KARL AUGUST MEUMANN and MAX JOSEPH HIRSCH, citizens of the Kingdom of Saxony, German Empire, residing at Schönau, near Chemnitz, Kingdom of Saxony, Germany, have invented a new and useful Sewing-Machine for Manufacturing Smocked plaits, of which the following is a specification.

10 The invention has for its object a sewing-machine for the manufacture of smocked plaits in fabrics in such a manner as to make them elastic and closely-fitting, to which end the material is plaited and the plaits are sewed together at predetermined intervals at alternate places.

There are known Singer or other sewing-machines on which the plaits in the material are sewed together by means of a single needle 20 by a continuous thread at alternate places. In this machine, however, the plaited material must be moved intermittently to and fro in the longitudinal direction of these plaits from stitch to stitch beneath this one needle.

25 The smocked plait is formed only after the material has been twice passed through the machine. As compared with this known process, the present invention exhibits the essential improvement that the material is 30 passed through the machine once only and in one and the same direction, this being rendered possible owing to the fact that the material plaited transversely to its direction of feed is sewed simultaneously throughout the desired width by a series of needles—that is 35 to say, by at least two needles. By this means the output is largely increased. Further, threads of different color may be employed for the different needles, so that by

40 forming knots differently-colored smocked plaits with ornamental effects may be produced. In order that while utilizing a number of needles and threads strong knots which are not liable to come undone may be formed 45 automatically, two stitches are made for each knot, and each stitch is passed through the loop of the other, so that chain-stitches are formed. Each needle passes alternately through two holes, so that the thread of each 50 stitch is interlaced with the loop of the preceding stitch. The sewing-machine for carrying this method into practice is broadly characterized by a row of horizontal needles, which each coöperate with a double loop-

taker displaceable in a plane upward and 55 downward and to and fro; also, by a material-holder displaceable to and fro and upward and downward, in which holder a vertically-movable stitch-plate is arranged for plaiting. This material-holder is provided with an appropriate presser-foot and also a material-feeder.

Figure 1 is a section through the sewing-machine on the line A A of Fig. 2. Fig. 2 is a plan of the machine. Fig. 3 is a section 65 taken on the line X X of Fig. 2. Fig. 4 is a detail view showing the lever S and cam q in elevation and the holder k and stitch-plate i in section. Fig. 5 is a vertical section on the line B B of Fig. 6, and Fig. 6 is a front elevation of the material-holder with the stitch-plate, feeder, and the loop-taker. Figs. 7- 70 22 illustrate diagrammatically the formation of the knots and plaits. Figs. 23 and 24 are respectively upper and under views of the 75 goods, and Fig. 25 illustrates diagrammatically the path of the thread in the formation of the knots, the holder k not being shown in this figure.

The machine comprises any desired number 80 of horizontal needles a, (in the present example four,) which are mounted in a reciprocating needle-holder b. This latter receives its movements from a cam c and link d, Figs. 1 and 2. The cam c is mounted upon 85 the shaft e, from which the loop-takers 2 hereinafter described, the material-holder k, and the stitch-plate i also receive their movements. The shaft e is driven by means of a train of gearing f from a shaft g, which is provided with a cord-pulley h, provided with a suitable handle.

The stitch-plate i, which is movable upward and downward in the material-holder k, coöperates with the horizontal needles. 95 This plate lifts the material l, which is placed upon the material-holder for the formation of a plait in which knots are formed. The stitch-plate is provided with vertical slots to permit of the unimpeded passage of the 100 needles. When the formation of the knots is finished, the stitch-plate descends in the material-holder and the tied plait is turned over toward the rear side of the material-holder k. This is effected by means of a 105 spring-controlled cover-like material-feeder m, Figs. 5, 6, 19, and 20, which bears against the upper edge of the stitch-plate and upon

the descent of the stitch-plate depresses the plait. On its lower edge this cover *m* is provided with recesses *n* for the free passage of the needles. The upper or lower edge of the cover *m* is provided with openings *o* for the engagement of material presser-feet *p*, which firmly retain the tied plait on the material-holder *k* until the completion of the tying of a fresh plait.

10 The stitch-plate *i* receives its upward and downward movement from a cam-plate *q*, mounted on the shaft *e* by means of a lever *s*, Figs. 2 and 4, rotatably mounted at *r*, the front arm of this lever passing through the material-holder *k* into the stitch-plate. Upon each complete revolution of the shaft *e* the stitch-plate *i* is twice depressed, owing to the fact that the projections of the cam *q* raise the rear arm of the lever *s*. A spring *t*, 15 acting upon the rear arm of the lever *s*, again lifts the stitch-plate *i*.

For the formation of honeycombed or smocked work—that is to say, for the formation of plaits of rhomboidal form, Fig. 23—it is necessary that the knots of each plait should be alternate with or be displaced relatively to those of the adjacent plait. In the present case this is effected by lateral displacement of the material-holder *k* in one direction or the other. To this end the material-holder *k*, together with the stitch-plate *i*, the material presser-feet *p*, and the feeder *m*, are mounted upon a carriage *u*, displaceable horizontally, Fig. 3. From a cam-plate *v*, secured on shaft *e*, motion is communicated to carriage *u* through joint-arm *w*, linked to carriage *u* and entering cam-plate *v* by means of stud 14^x. On carriage *u* lies carriage *x*, arranged so that it can be shifted 20 horizontally and carrying the presser-feet *p*. Carriage *x* is moved by a cam-plate *y* through a spring-controlled arm *z*, secured to joint-arm *w*, so that it can turn. Carriages *u* and *x* are attached to a third slide 1, the latter being adapted to move vertically on the machine-frame through the action exerted thereon by a cam-plate 13, by the joint-arm *w*, and by the stud 14. Both studs 14 and 14^x of joint-arm *w* are so long that they gear 25 to a sufficient depth into their respective cam-plates 13 and *v* and that they are not thrown out of gear and disconnected from either cam-plate when an up-and-down motion or a reciprocating motion is imparted to joint-arm *w*. As a result of this arrangement in addition to being able to effect lateral movements the material-holder is able to effect, with the material, the stitch-plate, the feet, and the cover, movements upward and 30 downward also, the object of this being as follows: The tying is effected with a single thread for each needle. It is impossible to employ a two-thread stitch, owing to the difficulty of arranging shuttles or rotary loop-takers for loop formation. On the other

hand, however, an ordinary chain-stitch should not be used, because when this is damaged in one place it comes undone. It is for this reason that the present arrangement is adopted, so that each needle passes alternately through two holes and the loops of thread of the alternate stitches are interlaced one with the other, Fig. 25. In this manner strong knots, secure from coming undone, are formed automatically. To this end a double loop-taker 2 is provided for each needle, Fig. 6. The loop-taker consists of a vertical rod having two horizontal portions, the upper portion being provided with two downwardly-extending teeth 2' 2^a and the lower portion with two upwardly-extending teeth 2^b 2^c, the outer tooth of each pair being straight, while the inner one curves toward the outer tooth, so that the free ends of the two teeth are close together. The loop-takers move upward and downward in front of the material-holder *k*, also making lateral movements in order to arrange the loops. All the loop-takers are mounted upon an arm 3 above the material-holder and parallel with it, this arm 3 forming the rectangular prolongation of the front arm of a two-armed lever 4, Figs. 1 and 2. This lever is rotatably mounted upon a support 5, which is fixed upon a carriage 6, sliding horizontally in the frame of the machine. The carriage is provided with a tappet 7 in engagement with a cam-plate 8, Fig. 2, mounted upon the shaft *e*, which plate produces the lateral displacement in one direction of the carriage 6, and with it that of the loop-takers 2. Springs 9 draw back the carriage 6 with the loop-takers 2. The lever 4 is provided with a tappet 10, in engagement with a cam-plate mounted upon the shaft *e*, which plate, with the coöperation of a spring 12, acting upon the rear arm of the lever 4, rocks the said lever, thereby causing the loop-takers 2 to move up and down in front of the material-holder while they are effecting their lateral displacements.

The operation of the described machine on plaiting and sewing relatively displaced or alternating knots will be best understood by reference to Figs. 7-22. Fig. 7 shows the position of the material, of the stitch-plate, of the feet for pressing the material, and of the loop-takers at the beginning of the first stitch. The material *l*, which lies over the material-holder *k*, is lifted by the raised stitch-plate *i* and formed into a vertical plait which it is desired to sew. The needle *a* has passed through the plait and the upper loop-former on the loop-takers 2 and is about to move back. In the backward movement of the needle the loop-taker effects a movement upward and to the right, as indicated by the arrows in Fig. 7. Thereby the lower loop-former on the loop-taker 2 seizes the thread on the needle and tightens the loop, Fig. 8. 130

The first stitch is now completed. Before the second stitch is begun (this being made about two millimeters above the first stitch-hole) an appropriate down movement is imparted to the material-holder *k*, while the needles and loop-takers retain their position. Owing to the downward movement of the material-holder, the loop formed by the loop-taker assumes an upwardly-directed position, Fig. 9. The needle now moves forward in order to form the second stitch, passing through the loop of the first stitch, Fig. 10. During the return of the needle the loop-taker effects a downward movement and a lateral movement toward the left hand, the lower loop-former releasing the loop and the upper loop-former seizing the thread on the needle, Fig. 11. The second stitch is now finished. The material-holder *k* moves from the position represented in Fig. 11 to that shown in Fig. 12 in order to enable the needle to make the third stitch (in the first stitch-hole,) Figs. 12 and 13, in passing through the downwardly-drawn loop of the second stitch which was formed by the upper loop-former. During the return of the needle, Fig. 13, the loop-taker effects an upward movement and at the same time a movement toward the right hand. The upper loop-former releases its loop and the lower loop-former forms a fresh one on the needle, Fig. 14. The needle now begins to make its fourth stitch, which takes place in the second stitch-hole after the material-holder has effected its downward movement from the position represented in Fig. 14 into that shown in Fig. 15. The lower loop-former has then drawn upward the last loop of the first stitch-hole, Fig. 15, so that the needle, Fig. 16, may pass through this loop. During the return of the needle from this position, Fig. 17, the upper loop-former seizes the thread and the loop-taker makes a larger downward movement, so that a long depending loop, Fig. 18, is formed. The knot formed of four stitches is now finished and the preparations for the formation of the next plait and knot then take place. The stitch-plate *i*, which in Fig. 18 is still situated in the upper position, descends in the material-holder. During this descent of the stitch-plate the feeder *m* for the material, Fig. 19, brings the stitched or tied plait toward the rear side of the material-holder *k*, and the presser-feet, which shortly before ascended, again descend in order to firmly hold the tied plait on the material-holder, Fig. 20. At the same time the stitch-plate *i* again ascends and forms a fresh plait in the material, Fig. 21. The last loop, Fig. 18, must be of such a length that it does not impede the formation of the fresh plait or of the lateral displacement of the material-holder in order that the tying of the fresh plait may be effected in positions displaced relatively to

those of the previous plait. Fig. 22 is a view corresponding to Fig. 18, showing the ready-tied fresh plait before it is fed onward. Fig. 25 renders the path of the thread during the formation of the knots intelligible. The thread 16 first of all passes through the first stitch-hole 17 and back, forming the loop 18, then through the second stitch-hole 19, through the loop 18, and back through the hole 19. The thread then passes again through the first stitch-hole 17, forms the loop 20, passes through this same hole back to the hole 19, thence through the loop 20 to the loop-taker 2, where it forms the large loop 21, and from there it passes through the stitch-hole 19 and around the material-holder 80 to the needle *a*.

In the constructional form of sewing-machine here represented the needles are reciprocated eight times to each complete revolution of the shaft *e*. As a result upon each revolution of the shaft *e* two plaits are formed and sewed. After the needles have completed four stitches they come to rest, and in order to produce this idle period the cam-plate *c* is formed with two long concentric guideways at diametrically opposite places. During this idle period of the needles the sewed plait is removed by the feeder *m*, the material-holder *k* is displaced laterally by half the needle interval, and the stitch-plate is raised for the purpose of forming a new plait.

It should be understood that the construction of the machine may be modified in many ways in accordance with the nature and arrangement of the operating means and mechanisms without departing from the spirit of the invention.

Having now particularly described and ascertained the nature of our said invention and in what manner the same is to be performed, we declare that what we claim is—

1. A machine for producing waved or smocked plaits comprising a plurality of reciprocating needles with means for operating them, means for carrying a thread to each needle consisting of a double-loop taker for each needle, means for holding the material in plaits transversely of the path of the needles, and means for causing the needles and their threads to pass alternately through two holes in the plaits for each knot which is formed in such a manner that the thread-loops of the alternating stitches are interlaced with each other by the loop-takers.

2. A sewing-machine for producing waved or smocked plaits comprising a plurality of horizontally-arranged reciprocating needles, a needle-bar for carrying said needles, a material-holder, and a stitch-plate reciprocating vertically and coöperating with the material-holder to form a plait at right angles to the needles, a double-loop taker having a vertical

and horizontal reciprocating movement and a disk *c* for giving such movements to the loop-taker and for operating the needle-bar.

3. A sewing-machine for producing waved or smocked plaits comprising a plurality of horizontally-arranged reciprocating needles, a needle-bar for carrying such needles, a material-holder, and a stitch-plate reciprocating vertically and coöperating with the material-holder to form a plait at right angles to the needles, a flap for pressing down the sewed

plait upon the removal of the stitch-plate and a double-loop taker having a vertical and horizontal reciprocating movement a disk *c* for giving such movement to the loop-taker 15 and for operating the needle-bar.

EMIL KARL AUGUST MEUMANN.
MAX JOSEPH HIRSCH.
